UNITED STATES PATENT OFFICE.

JASON GILES, OF INDIAN ORCHARD, MASSACHUSETTS.

DESIGN FOR A HAND-WHEEL FOR VALVES.

SPECIFICATION forming part of Design No. 25,527, dated May 19, 1896.

Application filed February 8, 1896. Serial No. 578,611. Term of patent 14 years.

To all whom it may concern:

Be it known that I, JASON GILES, a citizen of the United States, residing at Indian Orchard, in the county of Hampden and State of Massachusetts, have invented a new and useful Design for Hand-Wheels for Valves, &c., of which the following is a specification, reference being had to the accompanying drawings, forming part thereof.

10 Figure 1 is a face view of a hand-wheel, showing my design. Fig. 2 is a cross-section thereof.

15 The letter *a* designates the rim of the wheel, which rim is substantially round in cross-section; *b*, the central hub, and *c* the web which unites said rim to said hub. Within said web *c* are located a plurality of panel-shaped openings *d*, which are concentric to the hub and have rounded ends, as shown. Between the 20 line of the inner edges of said openings and the hub is located a panel-shaped opening *e*,

which is also concentric to the hub and forms substantially one-half of a complete circle around the latter. Spanning said opening *e* are a series of cross-bars, some of which are 25 straight and truly radial to the hub *b*, others of which are straight and at an angle to the radius, and still others of which are curved. Upon the opposite side of the hub *b* is a 30 broken arrow, in relief, arranged concentrically to the hub, an open space between the head and tail of the arrow being left to receive any desired lettering.

Having thus fully described my design, what I claim is—

35 The design for hand-wheels for valves &c., herein shown and described.

JASON GILES.
